ATTORNEY

UNITED STATES PATENT OFFICE

BLAISE BUDAI, OF BAYSIDE, NEW YORK

NECKTIE HOLDER

Application filed April 5, 1928. Serial No. 267,713.

The present invention relates to improvements in necktie holders.

The main object of the invention is to provide a device of this character which can be easily and securely attached to the shank of an ordinary collar button and serves to keep the tie in place, that is to say it prevents the tie from moving about the button in any direction.

10 Another object of the invention is to produce a device of the character mentioned which has a tendency to cause the tie to bulge or set out, so as to give the knot of the tie more prominence.

15 A further object of the invention is to provide a device of the character mentioned which is simple in construction, efficient in operation, durable in use and capable of manufacture on a commercial scale, or in 20 other words one which is not so difficult to produce as to be beyond the reasonable cost of such a contrivance.

With these and other objects in view, which will more fully appear as the nature of the 25 invention is better understood, the same consists in the combination, arrangement and construction of parts hereinafter described, pointed out in the appended claim and illustrated in the accompanying drawings, it being understood that many changes may be 30 made in the size and proportion of the several parts and details of construction within the scope of the appended claim, without departing from the spirit or sacrificing any 35 of the advantages of the invention.

One of the many possible embodiments of the invention is illustrated in the accompanying drawings, in which:—

Figure 1 is a perspective view of a collar 40 and a tie in operative relation thereto, illustrating the use of the improved necktie holder and showing the manner in which the same acts to hold the tie in position in relation to the collar; Fig. 2 is a perspective view of the 45 improved device on a collar button; and Fig. 3 is a longitudinal section taken through a collar button and the improved device thereon.

Referring now to the drawings, the number 50 al 10 indicates a fold collar, comprising a

band 11 and a folded over top 12. The usual tabs of the band are provided with front buttonholes, adapted to be engaged by a button 13, the latter being extended through the front button holes of the collar band of the shirt to which the collar is to be attached.

The necktie holder is constructed of a single piece of metal 14, and comprises a bifurcated shank 15, the outer ends of the tines 16 of the bifurcated portion of the shank 15 being bent substantially at right angles to the body portion thereof, and are adapted to straddle the shank 17 of the collar button. The opposite end of the bifurcated shank 15 is in the form of a point or pin 18, which is adapted to enter the necktie. On the bifurcated portion of the shank 15 are formed lugs 19, which extend in a direction opposite to the outer bent ends 16 of the tines.

The operation of this device is as follows: The tie is first mounted upon the collar in the usual manner. The outer free ends 16 of the tines of the device are then engaged with the button shank 17, the button head holding the same securely in position thereon. When the tie holder has thus been arranged in position on the collar, the pin 18 of the device is caught into or engaged with the rear side of the tie, preferably below the knot or bow thereof, thus supporting or holding the tie in position and preventing any sagging thereof and consequent exposure of the collar button and untidy appearance of the necktie. As appears from Fig. 1 of the drawings, the holder is extended at an acute angle to the shank of the collar button and thereby causes the tie to bulge out. This is also due to the fact that the lugs 19 extend upwards, that is to say out of the plane of the holder. Another purpose of these lugs is to prevent the holder from disengaging itself from the tie, one or both of the same entering the folds in the rear face of the knot or bow.

The necktie holder constructed as herein shown and described is simple and inexpensive in construction, it being obvious that it can be made by stamping operations from a blank of sheet material, preferably metal. It is reliable and efficient in operation, and

may be readily applied to and removed from the collar button.

What I claim is:—

5 A necktie holder made of a single piece of material and comprising a bifurcated shank having the free ends of its tines bent at an angle to the body portion thereof and adapted to straddle the shank of a collar button, the opposite end of said shank being in the form of a pin, said pin being disposed in the plane of said shank and being capable of entering 10 a necktie, and two lugs formed on the bifurcated portion of said shank, said lugs extending in a direction opposite to that in which 15 the free ends of the tines of said shank are bent.

Signed at New York, in the county of New York and State of New York, this 7th day of March, A. D. 1928.

BLAISE BUDAI.
